United States Patent Office

Des. 184,130
Patented Dec. 23, 1958

184,130

HARD SURFACE FLOOR COVERING OR SIMILAR ARTICLE

Leona G. Kolker, Brooklyn, N. Y., assignor to Con-goleum-Nairn Inc., Kearny, N. J., a corporation of New York

Application April 29, 1958, Serial No. 50,658

Term of patent 14 years

(Cl. D92—17)

The figure is a plan view of a hard surface floor covering or similar article showing a full repeating unit between the dashed lines thereof.

I claim:

The ornamental design for a hard surface floor covering or similar article, substantially as shown.
